(57) **CLAIM**

The ornamental design for a nut moving device, as shown and described.

DESCRIPTION

FIG. 1 is a front perspective view of the nut moving device.

FIG. 2 is front view of the nut moving device.

FIG. 3 is back view of the nut moving device.

FIG. 4 a left view of the nut moving device.

FIG. 5 is a right view of the nut moving device.

FIG. 6 is a top view of the nut moving device; and,

FIG. 7 is a bottom view of the nut moving device.
